UNITED STATES PATENT OFFICE.

JOHN W. ASHWORTH, OF NEW YORK, N. Y.

COMPUTING-SCALE.

14,727.

Specification of Reissued Letters Patent. Reissued Sept. 23, 1919.

Original No. 1,197,586, dated September 12, 1916, Serial No. 709,347, filed July 15, 1912. Application for reissue filed May 12, 1917. Serial No. 168,308.

To all whom it may concern:

Be it known that I, JOHN W. ASHWORTH, a citizen of the United States, residing in the city and county of New York and State of New York, have invented certain new and useful Improvements in Computing-Scales, of which the following is a specification.

This invention relates to weighing scales and has particular reference to the computing types thereof.

The objects of the invention are to increase the accuracy of the readings of the scale's computations, to make the scale adjustable to the scale-reader's height so as to further facilitate correct readings, and to provide separate and distinct charts showing the pounds unencumbered by the markings showing the money values.

To these ends the invention consists in the novel construction of scale, combination and arrangement of parts, as hereinafter described in detail, illustrated in the accompanying drawing and incorporated in the appended claims.

25 In the drawing—Figure 1 is a front elevation of a complete scale embodying my invention.

Fig. 2 is an enlarged transverse section of the cylindrical upper part of the scale.

30 Fig. 3 is an enlarged view, partly broken away, of the revolving cylindrical portion which contains the money value chart and reading lines and the hands or indicators which coöperate with the pound-indicating charts on the two ends of the upper casing.

Fig. 4 is an end view of the upper casing showing one of the pound charts or scales.

Fig. 5 is a broken away portion of the chart and wire.

Figs. 6, 7 and 8 show modifications in the construction of wire-grooves or spaces and reading-line wires, and

Fig. 9 is a fragmental section on the line 45 9—9 of Fig. 4.

In the usual construction of this class of scales the reading line extends some distance in front of the chart, or away from it, and necessarily so in order to avoid friction between the chart-bearing drum or cylinder and the wire, scale or bar forming the reading line or on which same is marked. The result is that the line of sight may strike the chart either above or below the horizontal plane of the reading line according to the

height of the reader, thereby occasioning, in either instance, more or less inaccurate readings, incident to the resulting parallax. If the reader is a short person and the reading line is elevated above the horizontal plane of his eyes his line of sight will strike the chart above the reading line, and if he is a tall person his line of sight may strike the chart below the horizontal plane of the reading line. In my improved construction the reading line is arranged substantially on the circle of the chart-lines or aline with the chart-line that is to be read. My improvement also contemplates variations in the height of the position of the chart or cylinder itself above the base of the scale so as to bring the reading line into or near to the horizontal plane of the user's eyes, or, in other words, to make his line of vision as nearly horizontal as possible.

In the several views 2 represents the base of an ordinary form of scale which is the receptacle for the usual mechanism contained in said base.

3 is the upper portion of the scale, which in this instance is of a well known cylindrical form and represents a shell or casing within which is rotatably mounted on a shaft 4 a cylinder 5 containing a chart or graduations 6 or other suitable computing characters which are made visible to the operator through an opening 7 covered with a glass 8. On the cylinder 5 is mounted a series of rings or bands 9, 10, 11, 12 and 13 which are spaced apart to leave grooves 14, 15, 16 and 17 in each of which back of the glass 8 is mounted a wire 18 the ends of which wire are secured by soldering or otherwise, to the inner periphery of the cylindrical casing 3 as shown in Fig. 2. On substantially the middle of the wire 18 is a dot or mark 19, these dots being alined to form what is termed the "reading line." The reading line marks on the wires are arranged flush with the chart-surface of the rotating cylinder 5 by arranging the marked portions of said wires in the grooves as shown.

In Figs. 6, 7 and 8 instead of the bands or rings 9 to 13 on the drum 5 the latter is provided with corrugations 20 that are semi-circular in cross section or rectangular corrugations 21 which take the place of the bands or rings. In said modified views the wire 18 is also shown in the form of a flat

wire or strip of metal 22 or of half round form 23. Many other modifications may be made in these details.

By placing the reading point or line of the 5 wire 18 in the manner indicated the reading line will be the same for tall as for short persons with reference to the marks or characters on the chart, being in the same plane as said characters with reference to the line 10 of vision, or in other words, in the plane of said line of vision.

Referring, now, to the adjustment of the chart-portion of the scale with reference to the base-portion, 24 and 25 represent bent 15 supports or uprights which extend from the casing 3 and have their lower ends slidably adjustable in socket portions 26 and 27 which rise from the base 2 and are adjustably supported in said socket portions by 20 means of set screws, or other suitable means, 28 and 29. These telescoping parts may be extended to the number desired according to the range of adjustment required, the invention not being restricted to the particular 25 construction shown.

The pound markings are on annular dials 6' on the ends of the case 3, as shown in Fig. 4. An indicator, pointer or hand 4' is arranged on each end of the shaft 4 in the 30 plane of the dial 6', as shown in Figs. 1, 4 and 9 to coöperate with the pound-markings 6', thereby avoiding the inaccuracies of reading incident to parallax. Thus the device is provided, at each end, with a stationary pound chart having a movable hand mounted on, and actuated by, the shaft 4, which carries the revoluble chart. The pointer at each end is thus alined with each graduation that it points to which insures 35 the same accuracy in reading that the arrangement of the reading line for the cylindrical chart affords. The simple and easily understood pound scale is thus preserved in connection with the computing 40 scale without the addition of any mechanism other than the provision of the 45 pointers 4'.

Having thus described my invention, I claim as new and desire to secure by Letters 50 Patent:

1. The combination with a casing, of a cylindrical chart rotatably mounted within said casing, said chart having a circumferential series of graduations thereon, and 55 having an annular depression or channel in its periphery, and an indicator arranged to be alined with each of said graduations in said depression or channel.

2. The combination in a computing scale, 60 of a cylinder having a chart thereon with peripheral graduations thereon and a series of channels in its periphery and a reading line composed of a series of alined indicator points mounted in said channels substantially on the circle of said graduations.

3. The combination with the revolving cylindrical chart of a computing scale having a series of annular depressions therein and graduations marked thereon, of a reading arranged substantially in the circle of 70 said graduations, and means for elevating or lowering said reading line.

4. The combination with the reading chart cylinder of a computing scale, having a series of annular grooves in its outer 75 periphery, of a series of upright wires having a reading line thereon, said wires having their reading line portions arranged in said grooves, a base upon which said cylinder is mounted and adjustable telescopic 80 standards connecting said base and cylinder.

5. In a computing scale the combination with a revoluble money-value chart, of a stationary indicating point or reading line wire, a pointer mounted on the axis of said 85 money-value chart, a stationary pound-chart, and means for adjusting the height of said charts to adjust same to the vision of the reader of said charts and point and pointer. 90

6. In a weighing scale, weighing mechanism, in combination with weight indicating mechanism embodying a chart provided with annularly disposed graduations, and a coöperating indicator positioned immediately adjacent the inner circumference of the annularly disposed graduations, which chart and indicator are relatively movable by the weighing mechanism and which indicator is positioned to be brought by such 100 relative movement so that any particular graduation may be made to appear to be a prolongation of the indicator, into substantial alinement with the individual graduations, whereby errors in scale reading, due 105 to parallax, are obviated.

7. In a weighing scale, weighing mechanism, in combination with weight indicating mechanism embodying a chart provided with a series of annularly disposed graduations, 110 and a pointer coöperating therewith, and actuated by, the weighing mechanism, said pointer being of such length, and so positioned that the reading end thereof is movable directly adjacent the inner circumference 115 of said series of graduations and is adapted to come into substantial alinement with each individual graduation so that any particular graduation may be made to appear to be a prolongation of the pointer. 120

8. In a weighing scale, weighing mechanism, in combination with weight indicating mechanism embodying a chart provided with a series of graduations, and a coöperating indicator, which chart and indicator are relatively movable by the weighing mechanism, and which indicator is positioned to be brought, by such relative movement, into substantial alinement with the individual graduations, said graduation be- 125 130

- ing so positioned relative to the indicator that when the indicator is in alinement with any particular graduation, said graduation appears to be a prolongation or continuation 5 of the indicator whereby errors in scale reading, due to parallax, are obviated.
9. In a weighing scale, weighing mechanism, in combination with weight indicating mechanism embodying a chart provided 10 with a series of graduations, and a pointer coöperating therewith, and actuated by, the weighing mechanism, said pointer being so positioned that the reading end thereof is adjacent the graduations and is adapted to 15 come in substantial alinement with each individual graduation and make it appear that the graduation is a prolongation or continuation of the pointer.
10. In a weighing scale, weighing mechanism, in combination with weight indicating mechanism embodying a chart provided 20 with annularly disposed graduations, and a coöperating pointer revolute in substantially the same plane as said chart and actuated 25 by the weighing mechanism, the outer end of the pointer terminating directly adjacent the inner circumference of the annularly disposed graduations so that when the pointer is registering with any particular 30 graduation, such graduation appears to form a continuation or prolongation of the pointer whereby accurate readings of the chart may be made at all times even though the line of vision of the reader does not 35 aline with the axis of revolution of the pointer.
11. In a weighing scale, weighing mechanism, in combination with weight indicating mechanism embodying a chart provided 40 with a series of annularly disposed graduations, and a revolute pointer actuated by the weighing mechanism positioned substantially in the plane of said chart and actuated by the weighing mechanism, said pointer 45 being of such length that its reading end extends directly to the inner circumference of said series of graduations, so that when the pointer is registering with any particular graduation, such graduation appears to be 50 a prolongation or continuation of the pointer whereby it is adapted to be brought into substantial alinement with each individual graduation thereby obviating errors in scale reading, due to parallax.
- 55 12. In a weighing scale, weighing mechanism, in combination with weight indicating mechanism embodying a chart provided with a series of annularly disposed graduations, and a revolute pointer actuated by 60 the weighing mechanism, the pivotal mounting of which pointer is positioned below or rearwardly of, the plane of the chart, whereby said pointer is positioned substantially in the plane of the chart and can be brought 65 into alinement with the graduations indi-

vidually, the outer end of said pointer terminating directly adjacent the inner circumference of the annularly disposed graduations, so that when the pointer is adjacent any particular graduation such graduation 70 will appear to be a continuation or prolongation of the pointer.

13. In a weighing scale, weighing mechanism, in combination with weight indicating mechanism embodying a chart, the face of 75 which is provided with a depression and upon the stepped-up or forward face of which is positioned a series of annularly disposed graduations extending radially of the chart outwardly from the inner circumference of the stepped-up portion thereof, and an indicator positioned within the depression of the chart and terminating immediately adjacent the inner circumference of the stepped-up portion of the chart, said 80 chart and indicator being relatively movable by the weighing mechanism to bring the indicator and each individual graduation into substantial alinement and in such relation to the graduation that such graduation appears 85 to form a continuation or prolongation of the indicator when the weighing mechanism is operated, whereby errors in scale reading, due to parallax, are obviated.

14. In a weighing scale, weighing mechanism, in combination with weight indicating mechanism embodying a chart, the face of 90 which is provided with a depression and upon the stepped-up or forward face of which is positioned a series of annularly disposed graduations extending radially of the chart outwardly from the inner circumference of the stepped-up portion thereof, and a pointer positioned within the depression of the chart and terminating immediately 95 adjacent the inner circumference of the stepped-up portion of the chart, which pointer and chart are relatively movable by the weighing mechanism and which pointer is so positioned that the reading end thereof 100 will lie substantially in the plane of the stepped-up portion of the chart, whereby the pointer and each individual graduation will be brought into substantial alinement 105 when the weighing mechanism is operated and the particular graduation with which the pointer is registering will appear to be 110 a continuation or prolongation of the pointer.

15. In a computing scale, weighing mechanism, in combination with weight and value mechanism, embodying a series of money value graduations, a series of weight graduations, and indicating means, said indicating 115 means and graduations being relatively movable by the weighing mechanism, and the indicating means being positioned to be brought into substantial alinement with the individual graduations by such relative movement between the parts, the graduation 120

with which the indicating means is alined forming a continuation or prolongation of the indicating means.

16. In a computing scale, weighing mechanism, in combination with weight and value mechanism, embodying a series of money value graduations, a series of weight graduations, and a revoluble indicator associated with each series of graduations, both of 10 which indicators are simultaneously operable by the weighing mechanism, and said indi-

cators being positioned to be brought into substantial alinement with the individual graduations of their associated series, through the operations of the weighing mechanism whereupon the alined graduations appear to be prolongations or continuations of the indicators.

In testimony whereof I have signed my name to this specification.

JOHN W. ASHWORTH.
